UNITED STATES PATENT OFFICE

HAROLD C. HUDSON, OF SWAMPSOOTT, MASSACHUSETTS, ASSIGNOR TO UNITED SHOE MACHINERY CORPORATION, OF PATERSON, NEW JERSEY, A CORPORATION OF NEW JERSEY

METHOD FOR USE IN THE MANUFACTURE OF BOOTS AND SHOES

Application filed May 19, 1924. Serial No. 714,347.

This invention relates to the art of making boots and shoes and particularly to methods of treating the margins and edge portions of the bottoms of boots and shoes to produce what are known as "close edges" and "thin edges", that is, edges in which the width of the exposed edge face of the bottom materials is reduced to a minimum and caused to lie in close relation to the upper, the invention being illustratively set forth with reference to its application to the treatment of shoe shanks.

The production of shoes having thin edge and close edge shanks which would meet the requirements as to fine appearance and accuracy demanded by the trade, particularly for welt shoes, has been a problem attended by considerable difficulty, and it is an object of this invention to provide a method by the employment of which close edge and thin edge shanks may be produced with a facility and uniformity heretofore unattained. Although the exemplification of the invention herein illustratively set forth is designed to be especially applicable to the manufacture of welt shoes and, accordingly, the invention will be herein described with especial reference to welt shoemaking, it is to be understood that in various aspects the invention is not so limited and may be employed in the manufacture of shoes of other types which have a sole attaching flange.

In its application to the manufacture of welt shoes in one aspect the invention consists in providing the outsole with a thin flap or lip as by channeling, treating the margin of the sole which extends from ball line to breast line on each side of the shoe by reducing the width of the welt to an extent predetermined with relation to the width of the flap, reducing the width of the margin of the sole which extends beyond the channel flap to an extent predetermined with relation to the width of the welt when reduced to expose the margin of the welt, and reducing to a uniform thickness the margin of the welt which extends beyond the edge of the outsole. Preferably the margin of the outsole will be beveled from the base of the channel flap to a thin outer edge at a predetermined distance from the

edge face of the welt. Thereafter, the usual outsole sewing operation, to secure the welt and the outsole together, is performed, though it may be done earlier if desired, and the margins of the outsole and welt are beaten down to cause the welt to lie in close relation to the upper. The channel flap is cemented and laid to cover not only the beveled margin of the outsole but also the margin of the welt of uniform width which extends outwardly beyond it. After the formation of the heel-seat and the attachment of the heel in any well-known manner, the edge of the shoe is trimmed and set. In the edge-trimming operation at the shank of the shoe, as a result of the previous steps of this method, the trimming cutter acts, not on the sole, but only on the edge faces of the welt and the channel flap, and, by reason of the fact that the margins of the welt and flap are of uniform thickness, the trimmed edge face of the combined welt and flap will be of uniform width. Since the uniformity of thickness of the welt as well as of the flap extends inwardly for a predetermined distance, the trimming operator is allowed a certain latitude in the amount of material which may be removed without effecting the uniformity of thickness of the trimmed edge; a thin edge which is of uniform width and which lies close to the upper is thus produced.

The apparatus selected as illustratively embodying means by which certain steps of the method may be performed comprises a cutter by which the beveling of the margin of the outsole, the reduction of its width, the trimming of the sole attaching flange or welt to cause it to extend a predetermined distance beyond the edge of the outsole, and the reduction of the welt to a uniform thickness by removal of the material from the outer marginal face, are performed simultaneously by passing the shank portion of the shoe across the cutter. As illustrated, a shield runs in the rand crease of the shoe to limit the amount of material which may be removed from the edge face of the welt and has a face cooperating with the edge of the cutter which removes material from the outer marginal face of the welt to cause that portion of the welt to be

reduced to a uniform thickness. Beyond the said cutting edge the peripheral margin of the shield is concaved to reduce the effort required to move the shoe relatively to the cutter. Upon the opposite side of the cutter a second shield is provided which has substantially the same diameter as the cutter and is provided with a beaded edge which runs along the base of the channel flap and, by engagement therewith, serves as a guide for the shoe and a guard to prevent the beveling cut on the outsole from extending inwardly too far. Preferably the bead of the shield is on the side of the shield next to the cutter and the extreme points of the cutter blades are let into the bead. The extreme points of the cutter blades are thus shielded by the bead which prevents the cutter from digging and results in cleaner and more accurate operation of the cutter.

In the drawings,

Fig. 1 is a partial transverse section of the shank portion of a shoe in the condition in which it is presented after the rough-rounding and channeling operations, the dotted line indicating the line of cut for producing a thin edge;

Fig. 2 is a perspective view of the shank portion of a shoe after the operations of beveling the margin of the outsole, reducing its width, reducing the margin of the welt to uniform thickness and reducing its width have been performed;

Fig. 3 is a partial cross-section of Fig. 2;

Fig. 4 is a partial cross-section of the shoe after the outsole sewing operation;

Fig. 5 is a partial cross-section of the shoe after the margins of the outsole and welt have been beaten down to produce a close edge;

Fig. 6 is a partial cross-section of the shank portion of the shoe after the channel flap has been laid to cover the margins of the sole and welt;

Fig. 7 is a perspective view of the shoe after the sole leveling operation;

Fig. 8 is a partial cross-section of the shoe after the edges of the welt and channel flap have been trimmed;

Fig. 9 is a partial cross-section of the shoe showing the action of the edge-finishing tool;

Fig. 10 is a perspective view of the shoe after its completion;

Fig. 11 is an enlarged longitudinal section of apparatus which may be employed for carrying out the method, the shoe being shown in cross-section in its relation to the apparatus;

Fig. 12 is an exploded view in perspective of parts shown in Fig. 11; and

Fig. 13 is an end view of the cutter shown in Figs. 11 and 12.

In Fig. 1 is represented a section of a welt shoe through the shank portion at a stage in its manufacture after the usual operations, including the sole laying, rough-rounding

and channeling operations, have been performed. The edge face of the outsole 2 and the edge face of the welt 4 have been roughly trimmed flush by the rough-rounding operation and the channel flap 6 has been cut from the margin of the outer face of the sole 2. In cutting the channel flap on the rough-rounding it is impracticable for the channel cut to extend quite to the sole edge, a very narrow bead 8 being sometimes left on the sole if the sole is of good quality. This, however, is always removed in the final edge trimming operations.

The margins of the outsole and welt are now treated in accordance with the present invention by operations by which the material outside the dotted line in Fig. 1 is removed. These operations consist in beveling the margin of the outsole from the base 10 of the channel flap to a thin edge 12 (Fig. 2) at a predetermined distance from the said base, the entire edge face of the sole and a portion of the width of the sole margin being removed and exposing the margin of the welt beneath it. The margin of the welt 4 is reduced in thickness from the thin edge 12 of the sole to the edge face 14 of the welt, the reduction from 12 to 16 (Fig. 3) being a continuation of the line of bevel of the outsole, and the reduction from 14 to 16 being on a line parallel to the opposite face of the welt so that for the width 14, 16 the welt is of uniform thickness. Sufficient material is also removed from the edge face of the welt to enable the channel flap 6, when laid, to reach to the edge face of the welt even after the distance from the base 10 of the channel flap to the edge face of the welt has been increased by bending the sole margin and welt toward the shoe to close the welt crease. Allowance is also made for the head 8, a little more being removed from the welt than would be required if the flap reached to the edge face of the sole. The shoe is now ready for the outsole stitching operation which may be performed in any usual manner, for example by the Rapid outsole stitching machine, the welt and outsole being secured together by stitches 18 as indicated in Fig. 4. It is to be noted, however, that the sewing may precede the described thin edging operations if desired. In that case it is better to make the angle of the bevel of the outsole more obtuse to ensure against contact of the cutter with the stitches.

The margins of the outsole and welt are next beaten down to close the welt crease as shown in Fig. 5. Cement is applied to the inner face of the channel flap 6 and the exposed margins of the welt and sole and the flap laid down, its outer edge reaching to or slightly beyond the edge face 14 of the welt, as indicated in Fig. 6.

The shoe is next leveled to shape the sole finally to the last and to rub down and shape

the channel flap and the portions of the outsole and welt covered by it; this condition of the shoe being represented by Fig. 7, where it will be seen that the edge of the channel flap 6 extends along the outer corner of the edge face 14 of the welt in a somewhat irregular manner and that the crease (Fig. 6) in the flap over the line 16 of the welt has been eliminated. The shoe is now ready for the attachment of the heel, the heel-seat of the outsole being fitted and the heel attached in any usual manner. After the heel is attached the edge of the channel flap 6 and the edge face 14 of the welt, which constitute the only bottoming materials exposed in the shank portion of the shoe, are trimmed by the edge trimmer. In this operation, the fact that the flap and welt are of uniform thickness for a substantial distance inwardly of their edges gives the operator a latitude in trimming so that the usual variation in the amount trimmed from the edge at different parts thereof produces no corresponding variation in the width of the trimmed edge which will be of uniform width throughout, as indicated in Fig. 10. The trimming cutter has a shield which engages the shoe between the upper and welt but this shield is so thin that it does not materially disturb the close relation of the welt and upper. Any separation of the welt and upper in edge trimming is, however, counteracted by the edge setting iron which, as indicated in Fig. 9, has a lip 20 which engages the margin of the shoe bottom and applies inward pressure while an edge finishing face 22 acts on the edge face of the shoe bottom. The result of these operations, as indicated in Fig. 10, is a shoe having a close shank with a thin edge or narrow edge face of uniform width.

In Figs. 11 to 13 is shown apparatus including a cutter by which the beveling of the margin of the outsole, the reduction of its width and the reduction of the margin of the welt to uniform thickness and to a uniform width from the edge of the outsole may be effected by a single operation. As shown in Fig. 11, the apparatus comprises a shaft 30 which may be the cutter shaft of a trimming machine such as an edge trimmer. A sleeve 34 fits snugly over the shaft 30 and is held thereon by a set screw 36. The outer end 38 of the shaft 30 is tapered to receive a slotted expanding sleeve 40 having a flange 42. Internally the sleeve 40 fits the tapered portion 38 of the shaft and externally is received in a sleeve portion 44 of a cutter the blades of which, shown as four in number, are indicated at 46. Outside the cutter is a shield 48 having a reduced portion 50 which enters the opening in the cutter sleeve and positions the shield with respect to the cutter. A screw 52 the head of which is counter-sunk in the shield 48, has a left-hand thread which engages a threaded hole in

the end of the shaft 30. Tightening of the screw forces the shield 48 against the cutter sleeve 44 and the cutter sleeve against the flange 42 of the expanded sleeve 40 which is thereby pushed inwardly of the tapered portion 38 of the cutter shaft and caused to expand to hold the cutter sleeve firmly on the shaft. The before-mentioned sleeve 34 which slides on a cylindrical portion of the shaft 30 has the outer portion of its opening enlarged at 54 to free it from contact with the cutter sleeve 44 and externally is provided with a flange 56 against which a shield 58 abuts. The shield rests against the inner face of the cutter blades and is co-extensive in diameter with the blades. The shield 58 may be of steel, brass or other metal and, under some conditions, it is advantageous to provide on the outer face of the shield next to the cutter a thin layer 60 of copper the outer edge of which is formed into a bead 62. This makes the shield easier to clean and prevents it from burning the leather. The bead may be arranged to lie just beyond the ends of the cutter blades 46 but preferably the bead is of the same diameter as the cutter and the extreme ends of the cutter blades are let into the bead, the bead being removed at the points 64 to receive the points of the cutter blades 46. The bead may be integral with and of the same material as the shield. The bead prevents the cutter from digging or cutting too deeply and results in cleaner and better operation of the cutter.

The cutting edge of each of the blades 46 has three cutting portions, an outer inclined portion 66, a portion 68 perpendicular to the axis of the cutter, and a portion 70 parallel to the axis of the cutter. The portion 70 removes material from the edge face of the welt, the portion 68 removes material from the outer margin of the welt, and the portion 66 acts mainly on the margin of the outsole. In order that the welt may be supported for the action of the cutting edge 68 the shield 48 is provided with a surface 74 parallel to the cutting edge 68 and radially co-extensive therewith. The surface 74 supports and confines the flexible welt for the action of the cutting edge 68 and also for the cutting edge 70 which trims its edge face. The edge 66 bevels the margin of the sole from the base of the channel flap outwardly for a predetermined distance and because the margin of the welt is reduced in thickness its action extends for the short distance 12-16 (Fig. 3) on to the margin of the welt. The outer margin 76 of the shield 48 beyond the surface 74 is concave and the shield brought to a thin dull edge at its periphery. The periphery of the shield 48 extends into the welt crease of the shoe, serving to guide and support it and to limit the action of the cutter inwardly of the shoe. Pressure of 130

the shoe against the cutter, as shown in Fig. 11, causes the welt to bend slightly and bear against the margin 76 of the shield 48. If this margin 76 is not concave considerable friction between the shield and welt is produced which the operator has to overcome in moving the shoe along the cutter. By making the margin 76 of the shield concave much of the frictional resistance of the shoe 10 is removed, the welt bridging more or less between the outer edge of the surface 74 and the peripheral edge of the shield.

The shield 68, or the bead 62 which forms part of it, engages the outsole at the base 15 of the channel flap and serves as additional guiding, supporting and limiting means for the shoe. The provision of the two shields gives the operator a certain amount of latitude in tipping the shoe without materially 20 affecting the action of the cutter. The parts of the welt and outsole held for the action of the cutter between the two shields being flexible, the shoe may be tipped to a certain extent and guided at times by the bead of 25 the shield 58, at times by the periphery of the shield 48, and at times by both shields acting together.

The various cutting edges of the cutter will be so proportioned that the width of the 30 welt will be reduced to an extent predetermined by the width of the channel flap, that the width of the sole margin will be reduced to expose the margin of the welt to an extent predetermined by the width of the welt when 35 reduced, and that the thickness of the welt will be uniform for a predetermined distance from its edge face.

The novel features embodied in the apparatus above described are not claimed herein but are made the subject-matter of a divisional application Serial No. 465,725 filed 40 July 3rd, 1930.

Having thus described my invention, what I claim as new and desire to secure by Letters Patent of the United States is:

1. That method of forming thin edges on 45 welt shoes which consists in providing an outsole-stitch-covering flap, reducing the width of the welt to an extent predetermined with relation to the width of the flap, and reducing the width of the sole to expose the face of the welt to an extent predetermined with relation to the width of the welt when 50 reduced.

2. That method of forming thin edges on 55 welt shoes which consists in providing a channel flap on the outsole coextensive with the margin of the outsole and welt, reducing the width of the welt to an extent predetermined with relation to the width of the flap, reducing the width of the sole to expose the bottom face of the welt to an extent predetermined with relation to the width of the welt when 60 reduced, and beveling the margin of 65

the sole from the base of the channel flap to a thin outer edge.

3. That method of forming thin edges on 70 welt shoes which consists in providing an outsole-stitch-covering flap, reducing the width of the welt to an extent predetermined with relation to the width of the flap, reducing the width of the sole to expose the face of the welt to an extent predetermined with relation to the width of the welt when 75 reduced and reducing the exposed portion of the welt to a uniform thickness.

4. That method of forming thin edges on 80 welt shoes which consists in providing an outsole-stitch-covering flap, reducing the width of the welt to an extent predetermined with relation to the width of the flap, reducing the width of the sole to expose the face of the welt to an extent predetermined with relation to the width of the welt when 85 reduced, and laying the channel flap to cover the margin of the sole and the exposed portion of the welt.

5. That method of forming thin edges on 90 welt shoes which consists in providing an outsole-stitch-covering flap, reducing the width of the welt to an extent predetermined with relation to the width of the flap, reducing the width of the sole to expose the face of the welt to an extent predetermined with relation to the width of the welt when 95 reduced, laying the channel flap to cover the margin of the sole and the exposed portion of the welt, and trimming the edges of the flap and welt to form the edge of the shoe bottom.

6. That method of forming thin edges on 100 shoes which consists in providing a shoe with a sole attaching flange, securing an outsole to the shoe, channeling the outsole, and reducing the width of the margin of the sole under the channel flap to permit the flap to engage the sole attaching flange whereby the material to be trimmed from the edge of the sole comprises only the channel flap and the sole attaching flange.

7. That method of forming thin edges on 105 the shanks of shoes which consists in providing a channel flap on the outsole of uniform thickness coextensive with the margin of the bottoming materials, reducing in width 110 a portion of said margin, reducing the remainder of said margin for a predetermined distance from its edge to a uniform thickness, cementing and laying the channel flap to cover the reduced margin, and edge trimming the margin within the region of uniform thickness.

8. That improvement in methods of forming thin edges which includes channeling an attached sole, and beveling and reducing the width of the margin of the sole from which the channel flap was split so that the channel flap will extend beyond the edge of the sole.

9. That method of forming thin edges on 120 shoes which consists in attaching a sole to 125

a shoe having a sole attaching flange extending to the edge of the sole, and then beveling and reducing the width of the sole margin to expose the outer portion of the sole attaching flange.

10. That method of forming thin edges on welt shoes which consists in providing an outsole-stitch-covering flap, beveling the margin of the outsole to a thin edge, removing material from the flesh face of the welt to reduce the thickness of the welt, and laying the outsole-stitch-covering flap over the beveled margin of the outsole and the reduced welt.

15. That method of forming thin edges on welt shoes which consists in providing an outsole-stitch-covering flap, beveling the margin of the outsole to a thin edge, reducing the margin of the welt to uniform thickness, 20 and laying the outsole-stitch-covering flap over the beveled margin of the outsole and the uniform margin of the welt.

25. That method of forming thin edges on the shanks of welt shoes which consists in providing a channel flap on the outsole coextensive with the margin of the outsole and welt, beveling the outsole to a thin edge and reducing the width of the sole margin to expose the welt, reducing the margin of the 30 welt for a predetermined distance from its edge to a uniform thickness, cementing and laying the channel flap to cover the margin of the outsole and welt, and trimming the margins of the flap and welt within the region of uniform thickness of the welt.

35. That method of forming thin edges on the shanks of welt shoes which consists in providing a channel flap on the outsole of substantially uniform thickness at its outer margin, beveling the margin of the outsole to a thin edge, said edge being located at a predetermined distance from the base of the channel flap and within the margin of the welt, trimming the margin of the welt to a uniform thickness for a predetermined distance from its edge, cementing and laying the channel flap, and trimming the margins of the flap and welt to produce an edge of uniform thickness.

40. That method of forming thin edges on the shanks of welt shoes which consists in rough-rounding the outsole and welt, channeling the outsole to provide a flap of substantially uniform thickness, beveling the outsole from the base of the channel flap outwardly to a line within the margin of the welt, reducing the exposed portion of the welt to a uniform thickness for a substantial distance from its edge, laying the channel flap to cover the bevel of the outsole and the reduced margin of the welt, and trimming the edge of the flap and the welt to provide an edge face of uniform width.

45. That method of forming thin edges on the shanks of welt shoes which consists in

rough-rounding the outsole and welt, channeling the outsole to provide a flap of substantially uniform thickness, beveling the outsole from the base of the channel flap outwardly and reducing the width of the beveled margin to expose the welt, reducing the exposed portion of the welt to a uniform thickness for a substantial distance from its edge, sewing the outsole and welt together, laying the channel flap to cover the bevel of the outsole and the reduced margin of the welt, and trimming the edge of the flap and the welt to provide an edge face of uniform width.

50. That method of forming thin edges on the shanks of welt shoes which consists in rough-rounding the outsole and welt, channeling the outsole to provide a flap of substantially uniform thickness, beveling the outsole from the base of the channel flap outwardly and reducing the width of the beveled margin to expose the welt, reducing the exposed portion of the welt to a uniform thickness for a substantial distance from its edge, beating the margin of the outsole and welt into close relation to the upper, laying the channel flap to cover the bevel of the outsole and the reduced margin of the welt, and trimming the edge of the flap and the welt to provide an edge face of uniform width.

55. That method of forming thin edges on shoes having a sole and a sole attaching flange extending to the sole edge which consists in reducing the width and thickness of the margin of the sole to expose the margin of the sole attaching flange.

60. That method of forming thin edges on shoes having a sole and a sole attaching flange extending to the sole edge which consists in forming on the sole a stitch-covering flap, reducing the width and thickness of the margin of the sole beneath said flap to expose the outer margin of said sole attaching flange, and laying the stitch-covering flap against the reduced margin of the sole and the exposed margin of the sole attaching flange.

65. That method of forming thin edges on shoes having a sole and a sole attaching flange extending to the sole edge which consists in forming on the sole a stitch-covering flap, reducing the width and thickness of the margin of the sole beneath said flap to expose the outer margin of said sole attaching flange, reducing the exposed margin of said sole attaching flange to uniform thickness, and laying the stitch-covering flap over the reduced margin of the sole and the reduced margin of the sole attaching flange.

70. That improvement in methods of trimming the edge of the bottom of an outsoled welt shoe which consists in reducing the thickness and the width of the margin of the outsole with a beveling cut that intersects the contacting surfaces of the outsole and the welt and simultaneously reducing the thickness of the margin of the welt by severing stock from

the said contacting surface of the welt in a plane parallel to the opposite surface of the margin of the welt.

21. That improvement in methods of treating the edges of the bottom of a welt shoe which consists in simultaneously beveling the margin of the outsole to a thin edge and reducing the width of said margin and simultaneously reducing the width and thickness of the portion of the welt exposed by reducing the width of the sole margin.

22. That improvement in methods of treating the edges of the bottom of a welt shoe which consists in providing a channel flap on the outsole, reducing the width of the sole margin beneath the flap and simultaneously beveling the margin to a thin edge, reducing simultaneously the width and thickness of the portion of the welt exposed by the reduction of the width of the sole margin, and then utilizing the flap to cover the beveled margin of the sole and the reduced margin of the welt.

23. That improvement in methods of trimming the projecting marginal portion of a shoe bottom which consists in forming the body portion of the outsole with a beveling cut that intersects its attaching face, forming the remainder of the edge portion of the shoe with parallel surfaces perpendicular to its edge face to facilitate the formation of an edge of uniform thickness, and trimming the edge portion of the shoe within the region of uniform thickness.

24. That improvement in methods of forming the margins of shoe bottoms which consists in beveling a portion of the projecting margin of the shoe bottom, and forming the remainder of the edge portion of uniform thickness to facilitate the formation of an edge of uniform thickness in the edge trimming operation.

25. That improvement in methods of forming the margins of shoe bottoms which consists in beveling a portion of the projecting margin of the shoe bottom, and forming on an adjacent portion of the remainder of the margin a surface parallel to its opposite face to facilitate the formation of an edge of uniform thickness in the edge trimming operation.

In testimony whereof I have signed my name to this specification.

HAROLD C. HUDSON.
